UNITED STATES PATENT OFFICE

112,183

DESIGN FOR A COMBINATION DESK UNIT

Jim I. Silvers, Chicago, Ill.

Application August 29, 1938, Serial No. 79,619

Term of patent 7 years

To all whom it may concern:

Be it known that I, Jim I. Silvers, a citizen of the United States, residing at Chicago, in the county of Cook and State of Illinois, have invented a new, original, and ornamental Design for a Combination Desk Unit, of which the following is a specification, reference being had to the accompanying drawing, forming part thereof.

In the drawing:

Fig. 1 is a front elevation of a combination desk unit showing my new design.

Fig. 2 is a side elevation of the same.

Fig. 3 is a top plan view of the same.

I claim:

The ornamental design for a combination desk unit, as shown.

JIM I. SILVERS.
